TROUSERS

Elliot Silverstein, 310 E. 92nd St.,
Brooklyn, N.Y. 11212

Filed Nov. 14, 1969, Ser. No. 20,096

Term of patent 14 years

Int. Cl. D2—227

U.S. Cl. D2—28

FIG. 1.

FIG. 2.

FIG. 3.

FIG. 5.

FIG. 6.

FIG. 7.

FIG. 1 is a front perspective view of trousers showing my new design;

FIG. 2 is a front elevational view thereof;

FIG. 3 is a side elevational view;

FIG. 4 is a cross sectional view taken on the line 4—4 of FIG. 2;

FIG. 5 is a rear perspective view of a second embodiment of the design shown in FIG. 1;

FIG. 6 is a front elevational view thereof;

FIG. 7 is a side elevational view; and

FIG. 8 is a cross sectional view on the line 8—8 of FIG. 6.

The dominant feature of my design resides in the triangular configuration of the trouser legs.

I claim:

The ornamental design for trousers, as shown and described.
